UNITED STATES PATENT OFFICE.

BURTON B. BENNETT, OF PLYMOUTH, MICHIGAN.

AIR-GUN.

1,052,123.

Specification of Letters Patent.

Patented Feb. 4, 1913.

Application filed January 27, 1911. Serial No. 605,042.

To all whom it may concern:

Be it known that I, BURTON B. BENNETT, a citizen of the United States of America, residing at Plymouth, in the county of Wayne and State of Michigan, have invented certain new and useful Improvements in Air-Guns, of which the following is a specification, reference being had therein to the accompanying drawings.

10 The invention relates particularly to air guns of the reciprocating barrel type, the latter serving as the means for compressing the spring.

One of the primary objects of the invention is the provision of means in a gun of this character for preventing firing until the barrel—after the spring has been compressed—is restored to its outer shooting position, the object being to eliminate any 20 possibility of injury by reason of the outward movement of the barrel projected by the released spring, or injury to the barrel abutment or seat resulting from the barrel being thrown forcibly against the latter.

25 A further object of the invention is to provide simple and effective means for guiding the plunger stem into engagement with the trigger, and a still further object is the provision of a construction wherein 30 the stem during the operation of firing is prevented from following the trigger, thereby insuring quick and effective separation of the parts.

With the several objects in view, the invention consists in the novel construction of the air gun, in the peculiar arrangement and combination of parts, and in various details of construction and in their arrangements and combinations, as will be more 40 fully hereinafter set forth and claimed.

For the purpose of illustration, I have shown my invention as embodied in a toy air pistol, in which—

Figure 1 is a vertical central longitudinal section, showing the parts in their relative positions immediately after firing; Fig. 2 is a similar view, showing the pistol in tensioning position; Figs. 3 and 4 are detached perspective views of the plunger and barrel; Fig. 5 is a similar view of the handle section; and Fig. 6 is an enlarged sectional perspective view of the trigger mechanism.

In the drawings thus briefly described, the reference letter A represents the handle section, composed of the handle proper or grip B, and an open-ended housing C.

D represents the reciprocating barrel mounted within the housing for longitudinal movement, and E is the usual plunger housed within the barrel and adapted upon 60 extreme outward movement to strike against an abutment α' formed by a re-bent section of the barrel extremity.

F represents the plunger stem, having a substantially circular cross section for a distance from the plunger, and for the balance of its length—indicated by the reference-letter b—preferably a polygonal cross section, the stem presenting a flat surface for abutment against the bottom of the barrel 70 for the purpose of preventing any relative rotary movement. At its inner end the stem terminates in a hook c adapted to engage the trigger, and immediately adjacent to the hook in a concave bend d the purpose 75 of which will be hereinafter set forth.

G represents the plunger spring, coiled about the stem, abutting at one end against the plunger head and at its opposite end against a cross pin J fixed within the forward portion of the open-ended housing B. This pin projects through longitudinal slots K in the barrel, and when the plunger is at its extreme outer position lies within the bend d in the stem, thus allowing the stem 85 to properly travel over the bottom portion of the spring.

L represents the trigger, mounted upon a pivot e extending crosswise through the housing at its rear end and through slots f 90 in the barrel. In addition to the usual detent g, the trigger is provided at its upper end with a projection h that normally bears against the top wall of the barrel except when the latter is in its outermost position, 95 when it is adapted to engage an aperture i in the barrel top, the opening being sufficient to allow enough movement of the trigger to disengage from the plunger stem. The finger portion j of the trigger projects 100 downwardly through a suitable slot k formed longitudinally in the bottom portion of the barrel for that purpose.

Referring to Fig. 1 of the drawings, where the parts are shown in the position 105 immediately after firing, to recharge or compress the spring the barrel is moved inwardly until the hook c engages the trigger detent. During this inward movement the trigger through its projection h described is 110 held in its stem-engaging position, the hook of the stem riding over the trigger detent

to permit of the engagement of the parts. It will be obvious from the foregoing description that the trigger is held in its locking or engaging position until the barrel is drawn forwardly preferably its entire distance, when the aperture *i* in the barrel end alines with the trigger projection. The trigger may then be rocked and the plunger released. In this manner, a positive locking means is provided, compelling the outward projection of the barrel in its proper shooting position before any firing can take place.

The cross pin *J*, in addition to serving as an abutment for the spring, acts as a guide for the stem, insuring the proper engagement of the latter with the trigger detent. This latter function is effected by the pin bearing against the top portion of the stem, causing the bend in the latter to travel upon the bottom of the barrel, and, through the curve of the stem, into proper engagement with the trigger. The bend *d* by contacting with the barrel acts as a support for the trigger-engaging portion of the stem, preventing any downward or follow movement of the latter with respect to the trigger during the operation of firing. Thus, a quick and effective break between the parts is provided for.

In most instances, the opening *i* formed in the upper wall of the rear end of the barrel is sufficient to afford the necessary play for the trigger to disengage from the stem. I may, however, and preferably do, form an alining opening *i'* in the open-ended casing into which the trigger projection may extend if necessary.

What I claim as my invention is,—

1. In an air gun, the combination with a barrel, of a spring-pressed plunger and its stem, a trigger engageable with the stem, the latter having a bearing portion in advance of the part of the stem engageable with the trigger adapted to engage the barrel for preventing follow movement of the stem relative to the trigger during the disengagement of the parts.

2. In an air gun, the combination with a handle section, of the spring-pressed plunger, a reciprocating barrel acting on inward movement to compress the plunger spring, a trigger for holding the spring in its compressed position, and means for preventing release of the spring until the barrel is restored to its outer shooting position.

3. In an air gun, the combination with a handle section, of a spring-pressed plunger and stem, a reciprocating barrel mounted upon the handle section and acting on in-

ward movement to compress the plunger spring, a trigger engageable with the stem for retaining the spring under compression, and a lock for preventing operation of the trigger until the restoration of the barrel to its outermost position has been effected. 65

4. In an air gun, the combination with a handle section, of a spring-pressed plunger and stem, a reciprocating barrel upon the handle section serving on inward movement to compress the plunger spring, a trigger 70 for engaging the stem after the compression of the spring has been effected, and a projection on the trigger bearing normally against the wall of the barrel and acting to hold the trigger against movement until the 75 restoration of the barrel to its shooting position has been effected.

5. In an air gun, the combination with a handle section, of a spring-pressed plunger and stem, a reciprocating barrel upon the 80 handle adapted upon inward movement to compress the plunger spring, a trigger for engaging the stem, and a projection upon the trigger bearing normally against the barrel top and adapted to engage an opening in the upper wall of the barrel at the 85 rear end of the latter.

6. In an air gun, the combination with a barrel, of a spring-pressed plunger housed therein provided with a stem, a trigger engageable with the stem, a pin extending transversely of the barrel forming an abutment for the spring, said stem being arranged beneath the pin, whereby the latter forms a guide for positioning the stem in 95 proper relation to the trigger during the charging or setting of the parts.

7. In an air gun, the combination with a handle section including an open-ended housing, a reciprocating barrel provided 100 with slots, a spring-pressed plunger including a stem, said barrel acting on inward movement to compress the plunger spring, a trigger for holding the spring in its compressed position, a cross pin carried by the 105 housing and extending through the slots in the barrel, forming a guide therefor, and an abutment for the spring, said pin being arranged above the stem, whereby it serves as a guide for positioning the stem in proper 110 relation to the trigger during the charging or setting of the parts.

In testimony whereof I affix my signature in presence of two witnesses.

BURTON B. BENNETT.
